UNITED STATES PATENT OFFICE.

EDGAR W. GORHAM, OF LYNDONVILLE, VERMONT.

BROOM-HOLDER.

1,109,413.

Specification of Letters Patent.

Patented Sept. 1, 1914.

Application filed May 10, 1912. Serial No. 696,440.

To all whom it may concern:

Be it known that I, EDGAR W. GORHAM, citizen of the United States, residing at Lyndonville, in the county of Caledonia and State of Vermont, have invented certain new and useful Improvements in Broom-Holders, of which the following is a specification.

This invention relates to devices for suspending brooms, mops and like implements by the handles, and has for one of its objects to improve the construction and increase the efficiency and utility of devices of this character.

Another object of the invention is to provide a simply constructed device which may be readily employed for suspending brooms, mops or like implements having handles of varying diameters without structural change in the device.

With these and other objects in view, the invention consists in certain novel features of construction as hereafter shown and described, and then specifically pointed out in the claims, and in the drawings illustrative of the preferred embodiment of the invention: Figure 1 is an edge view of the improved device applied and attached to a wall; Fig. 2 is a detached plan view of the improved device; Fig. 3 is a section on the line 3—3 of Fig. 2.

The improved device comprises a disk or plate 10 which may be of any required shape, but preferably circular and provided with an opening therethrough. At diametrically opposite sides of the opening 11, the metal constituting the body of the plate is permanently deflected in opposite directions to form rigid gripping members 12—13 offset with respect to the upper and lower faces of the plate, as shown, the upset 12 being directed from one face of the plate and the upset 13 being directed from the opposite side of the plate. By this simple means the opening is enlarged at two opposite sides so that when tilted a larger handle indicated at 14, may be inserted than could be inserted if the upset portions were not formed in the plate. By this simple arrangement it will be obvious that when a relatively small handle is to be supported the plate will be located so that the portions of the plate between the upsets will engage against the handle and the plate tilted to cause the metal to engage the handle as indicated in Fig. 1. If a larger handle is to be supported the plate is

tilted to a greater extent to enable the handle to be inserted and bear against the opposite portions of the plate. The plate is arranged to be supported from one edge only and an ordinary screw eye 15 will preferably be employed for this purpose. It will be noted that the screw eye is located opposite the upset portion 12 so that the two upset portions and the screw eye are substantially in alignment transversely of the plate. If a broom, mop or other implement having a relatively small handle is to be supported, the plate is turned laterally upon its screw eye support to enable the handle to be engaged against the portions of the plate between the upsets as above noted, and then when the weight of the implement comes upon the plate the latter will hang at an angle from its screw eye support, but will effectually hold the handle. By this simple arrangement a simple and convenient device is produced which may be inexpensively manufactured and is adapted to support handles of varying sizes, as above noted, without structural change in the device.

Having thus described the invention, what is claimed as new is:

1. As a new article of manufacture, a broom holder comprising a plate having a handle receiving aperture formed therein, stops arranged on each side of the plate adjacent the aperture, said stops being diametrically disposed and constituting permanent rigid gripping members offset with respect to the upper and lower faces of the plate.

2. As a new article of manufacture, a broom holder comprising a plate having a handle receiving aperture formed therein and entirely surrounded by the plate, the plate adjacent the aperture and at diametrically opposite points being pressed outwardly to form permanent rigid gripping members offset with respect to the upper and lower faces of the plate.

3. As a new article of manufacture, a broom holder consisting of a rigid metallic plate having an approximately centrally disposed orifice adapted to receive a broom handle, and integrally formed permanent rigid stops arranged at diametrically opposed portions of the orifice and produced by pressing the metal outwardly in opposite directions.

4. As a new article of manufacture, a

broom holder consisting of a rigid metallic plate having an approximately centrally arranged orifice, and permanent rigid gripping members formed integrally with the plate and arranged at diametrically opposed points in the orifice, the edges of said gripping members being offset with respect to the opposite faces of the plate, said grip-

ping members being adapted to engage the broom handle throughout their length.

In testimony whereof I affix my signature in presence of two witnesses.

EDGAR W. GORHAM.
